UNITED STATES PATENT OFFICE.

MELLE P. SMEDES, OF REEMAN, MICHIGAN.

GAS-LIGHTING SYSTEM.

1,261,964.

Specification of Letters Patent. Patented Apr. 9, 1918.

Application filed July 30, 1915. Serial No. 42,745.

To all whom it may concern:

Be it known that I, MELLE P. SMEDES, a subject of the Kingdom of Netherlands, and a resident of Reeman, in the county of Newaygo and State of Michigan, have invented a new and useful Improvement in Gas-Lighting Systems, of which the following is a specification.

My invention is an improvement in gas burners, and consists in certain novel constructions and combination of parts hereinafter described and claimed.

In the drawings:—

Figure 1 is a side view of a burner with the leak indicator in section,

Fig. 2 is an enlarged side view of the burner,

Fig. 3 is a vertical section of the burner, and

Fig. 4 is a side view of the nozzle.

The burner, as shown more particularly in Fig. 3, comprises a nozzle consisting of an internally threaded cap 55, for engaging the pipe 49, and the cap has an extension at its top comprising a cylindrical threaded portion 56, and a tapering plane portion 57.

The cap and the portions 56 and 57 are chambered as shown, the chamber or bore consisting of five portions gradually decreasing in diameter from the entrance of the cap to the exit at the apex of the portion 57. The threaded portion 56 of the extension is engaged with the lower end of a casing, comprising a cylindrical portion 58 and a spherical portion 59, the spherical portion having openings 60 as shown, adjacent to the cap. The extension is of such length that

when the cap is in place in the lower end of the spherical portion 59 the apex of the extension will be at the lower end of the cylindrical portion 58.

As shown in Fig. 2, a mantle 65 is provided for the burner, the mantle being supported by the usual holder 66, which is connected to the bracket 67 that supports the flue or chimney 68 of glass or the like, which encircles the flame and the mantle.

A cap 69 is connected with the cylindrical portion 58 of the casing, the said cap having a reduced portion 70 which fits around the cylindrical portion 58 closely as shown. The cap has a perforated top 71, and a screen 72 is arranged transversely of the top above the portion 58 of the burner. The bracket 67 has a holder 73 for the chimney or flue.

It will be noted that the cap is of smaller diameter than the mantle and extends within the lower end of the mantle.

I claim:—

A burner comprising a substantially cylindrical casing having at its lower end an approximately spherical enlargement provided with a series of air inlet openings at the end remote from the cylindrical portion, and a tapering nozzle detachably connected with the spherical enlargement at the said end remote from the cylindrical portion and extending through the enlargement and delivering at the junction of the enlargement to the cylindrical portion, the bore of the nozzle being stepped down toward its inner end.

MELLE P. SMEDES.
